Primary Examiner — Shannon W Morgan*Assistant Examiner* — Altaira J Swangin(74) *Attorney, Agent, or Firm* — Cowan, Liebowitz & Latman, P.C.(57) **CLAIM**

The ornamental design for an instrument panel for an automobile, as shown and described.

DESCRIPTION

FIG. 1 is a front view of the instrument panel for an automobile showing my design;

FIG. 2 is a front view thereof;

FIG. 3 is a top view thereof;

FIG. 4 is a bottom view thereof;

FIG. 5 is a left side view thereof; and,

FIG. 6 is a right side view thereof.

The broken lines in the drawings, illustrating a steering wheel and a display portion on the right side of the instrument panel for an automobile, form no part of the claimed design. Dashed lines offset from either side of a solid line represent stitching, the particular configuration of which forms no part of the claimed design.
